UNITED STATES PATENT OFFICE.

HARRY L. SPENCE, OF SANFORD, MAINE.

THREAD-CUTTER.

1,224,800.

Specification of Letters Patent.

Patented May 1, 1917.

Application filed August 16, 1916. Serial No. 115,349.

To all whom it may concern:

Be it known that I, HARRY L. SPENCE, a citizen of the United States, residing at Sanford, in the county of York and State 5 of Maine, have invented new and useful Improvements in Thread-Cutters, of which the following is a specification.

This invention relates to a thread cutter for connection with the bobbin lifting plate 10 associated with flier spinning, twisting, and analogous machines, which for instance may be of the type disclosed in the patent to Shackleton, 1,090,758, March 17, 1914, so that the thread cutter may be used to sever 15 threads connected with the bobbins on the lifter plate after the bobbins have been doffed.

The primary object of the invention is to provide a thread cutter of the class described 20 which is so constructed that at the beginning of the doffing of the bobbins, the cutter may be operated to knock from the bobbins, the drag washers associated therewith and after the bobbins have been doffed, the threads 25 connected therewith may be severed close to the bobbins so that no long ends are left upon the threads on the bobbins which would have a tendency upon the bobbins reaching the loom to cause the bobbins to 30 hang before the thread has been run off of the same.

With these and other objects in view, the invention resides in the novel combination and arrangement of parts, which will be 35 hereinafter described and particularly pointed out in the claims.

The preferred embodiment of the invention has been illustrated in the accompanying drawings, although no restriction is 40 necessarily made to the precise details of construction therein shown, as changes, alterations, and modifications within the scope of the claims may be resorted to when so desired.

45 Like characters of reference denote corresponding parts throughout the several views in the drawings, in which:

Figure 1 is a vertical sectional view through a portion of a spinning machine

showing the improved thread cutter applied 50 to the bobbin lifting plate thereon.

Fig. 2 is a top plan view of the bobbin lifting plate removed from the spinning machine and showing the washer plate on the thread cutter in an inactive position. 55

Fig. 3 is a view similar to Fig. 2 showing the washer plate on the thread cutter in active position.

Fig. 4 is a sectional view on the line 4—4 of Fig. 2. 60

Fig. 5 is a vertical transverse section on the line 5—5 of Fig. 2.

Fig. 6 is a view similar to Fig. 5 on the line 6—6 of Fig. 2.

Referring now to the drawings in detail, 65 the numeral 1 designates a portion of an end of a spinning machine with which is shown connected a portion of the bobbin doffing mechanism 2 having connected therewith a spindle rail 3 arranged below a bobbin lifting plate 4 adapted to have connected therewith the usual plate raising and lowering mechanism (not shown in the drawing), said lifter plate having passing therethrough and through the drag washers 5 70 thereon, spindles 6 mounted upon the spindle rail 3 and having connection with fliers 7 between the arms of which are arranged the bobbins 8 seated upon the drag washers 5 and having passing therethrough 75 the spindles 6. 80

Connected with the bottom face of the bobbin lifting plate 4 at spaced intervals throughout its length are spaced brackets 9 having heads 10 thereon extending beyond 85 one side edge of the bobbin lifting plate 4 and provided with bearing openings 11 in which is mounted for turning movement a sleeve 12 extending the entire length of the bobbin lifting plate 4 and spaced above the 90 upper face of said plate by the heads 10, said sleeve having formed therein at intervals throughout its length circumferentially arranged slots 13 and has connected therewith a plate 14 extending the entire length 95 of the sleeve and adapted to be brought into contact with the drag washers beneath the bobbins 8 in a manner presently described,

said sleeve having formed therein near one end an elongated and longitudinally extending slot 15.

Arranged within the sleeve 12 and extending the entire length thereof is a tubular cutter rod 16 one end of which extends beyond an end on the sleeve 12 and is provided with a loop 17 forming a hand hold by means of which the cutter rod may be slid longitudinally of the sleeve 12 to cause spaced and alined slots 18 in the peripheral surface thereof to pass beneath the alined slots 13 in the sleeve 12 so that when the slots 13 and 18 are in registration and the cutter rod 16 is slid longitudinally of the sleeve 12 in either direction, the side walls of the slots 13 and 18 act as cutting blades.

Extending laterally from the cutter rod 16 near the loop 17 is a pin 19 one end of which is received in the slot 15 in the sleeve 12, said pin limiting the sliding movement of the cutter rod 16 within the sleeve 12 and also enabling the sleeve 12 to be turned in the heads 17 by the cutter rod 16 to cause the plate 14 to be brought into contact with the drag washers 5 beneath the spindle 6, so that the drag washers may be knocked from the bottom of the bobbins at the beginning of the doffing of the bobbins or held upon the bobbin lifting plate after the bobbins have been doffed.

Through the provision of the tubular sleeve 12 and cutter rod 16, it will be seen that an extremely strong construction of thread cutter is provided which is not likely to bend or twist while in use and adds no unnecessary weight to the bobbin lifting plate of the spinning machine.

When the improved thread cutter is connected with the bobbin lifting plate of a spinning machine as shown in Fig. 1 in the drawings, the cutter may be used to knock the drag washers from the bobbins at the beginning of the doffing of the same or to cut the thread connected therewith after the bobbins have been doffed in the following manner:

When a series of bobbins 8 have been filled with thread, the spinning machine is stopped and the sleeve 12 oscillated in the heads 10 by means of the cutter rod 16 to cause the plate 14 to be brought into contact with the bobbins 8 so that when the mechanism (not shown in the drawing) connected with the bobbin lifting bar for lowering the same is operated to lower the bobbin lifting plate, the drag washers 5 may be simultaneously knocked from the bottom of the bobbins and held upon the bobbin lifting plate by the plate 14 as the bobbin lifting plate and the spindle rail are moved to their lowermost position.

Prior to the placing of the series of empty bobbins upon the bobbin lifting plate, the

plate 14 is restored to its normal position 65 by means of the loop on the cutter rod 16, so that the threads connected with the doffed bobbins are received in the slots 13 and 18 in the sleeve 12 and cutter rod 16, so that by moving the cutter rod 16 longitudinally of the sleeve 12 in either direction, the thread connected with the doffed bobbins may be severed in such a manner as to prevent long ends being left between the bobbins and the thread cutter which cause the 75 hanging of the bobbins when placed on the loom.

With the improved thread cutter in the position described, it will be seen that the series of empty bobbins may be placed on 80 the bobbin lifting plate and the bobbins moved to their normal position and the spindles connected with the fliers 7 so that the thread may be started upon the empty bobbins by suitable setting on mechanism 85 (not shown).

From the foregoing description, taken in connection with the accompanying drawings, it is at once apparent that a thread cutter for spinning machines has been provided which will not only cut the threads connected with doffed bobbins in an efficient manner but may also be used to knock the drag washers from the bobbins at the beginning of the doffing operation and to hold 95 the said washers upon the bobbin lifting bar until the doffing operation is completed.

Having thus described the invention, what is claimed as new, is:

1. In a device of the class described, in 100 combination, a bobbin lifting plate, a thread cutter connected with said bobbin lifting plate, and a washer engaging plate on said thread cutter.

2. In a device of the class described, in 105 combination, a bobbin lifting plate, a rotatable thread cutter connected with said bobbin lifting plate, and a washer engaging plate connected with the thread cutter.

3. In a device of the class described, in 110 combination, a bobbin lifting plate, a sleeve connected with said plate for turning movement, a washer engaging plate carried by said sleeve, and a cutter rod connected with the sleeve for turning the same. 115

4. In a device of the class described, in combination, a bobbin lifting plate, a sleeve rotatably connected with said bobbin lifting plate, a washer engaging plate carried by said sleeve, and a cutter rod for turning 120 said sleeve mounted to slide therein.

5. In a device of the class described, in combination, a bobbin lifting plate, a sleeve rotatably connected with said bobbin lifting plate and having spaced slots therein, a washer engaging plate carried by said sleeve, and a cutter rod mounted to slide in said sleeve and having connection therewith 125

whereby said sleeve may be turned by said cutter rod.

6. In a device of the class described, in combination, a bobbin lifting plate, brackets connected with said plate, a sleeve mounted to turn in said brackets and having spaced slots therein, a washer engaging plate connected with said sleeve, a cutter rod having

spaced openings therein and mounted to slide in said sleeve, said cutter rod having 10 connection with the sleeve to enable the same to be turned by the cutter rod, and an operating handle on said cutter rod.

In testimony whereof I affix my signature.

HARRY L. SPENCE.
